UNITED STATES PATENT OFFICE.

COLEMAN F. COOK, OF CINCINNATI, OHIO.

NON-REFILLABLE BOTTLE.

1,199,765.

Specification of Letters Patent.

Patented Oct. 3, 1916.

Application filed October 28, 1914. Serial No. 869,056.

To all whom it may concern:

Be it known that I, COLEMAN F. COOK, a citizen of the United States, residing at Cincinnati, in the county of Hamilton and State of Ohio, have invented certain new and useful Improvements in Non-Refillable Bottles, of which the following is a specification.

My invention relates to new and useful improvements in a bottle and more particularly to a bottle of the non-refillable type.

The primary object of the invention is the provision of a bottle of this character which is simple and inexpensive in construction and will have the outward appearance of the bottles now commonly in use.

A further object of the invention is the construction of a bottle having a frangible neck so that when the neck of the bottle has been broken it cannot be again sealed.

A still further object of the invention is the provision of a sealing cap which may be easily inserted in the neck of the bottle and cannot be removed.

With these and other objects in view the invention consists in the novel details of construction and arrangement of parts which will be more clearly understood from the following description and drawings, in which,

Figure 1 is a vertical section through a portion of the neck of the bottle. Fig. 2 is a top plan view with the seal in position. Fig. 3 is a top view of the sealing cap. Fig. 4 is a view in side elevation of the sealing cap, and Fig. 5 is a side elevation of a slightly modified form of the invention.

In the drawings, the numeral 1 indicates the neck of the bottle having the enlarged head 2 and a groove 3 is formed on the interior of the enlarged head 2. The neck is weakened, at 4, by means of a scratch so that the enlarged head 2 may be broken from the neck.

A flexible and expandable corrugated disk 5 of the shape shown in Figs. 3 and 4 of the drawings is provided for sealing the bottle. The disk 5 is normally in the contracted shape shown in Figs. 3 and 4, and when it is inserted into the bottle pressure is applied thereby expanding the disk so that the edges 6 will enter the groove 3 formed in the enlarged head 2. When the disk is expanded it will assume the diameter shown by dotted lines in Fig. 3. A cork disk 7 is received on the end of the neck beneath the sealing disk 5 and forms an air tight joint.

In the modified form of the invention as shown in Fig. 5, I have provided a bottle adapted to receive a cork after the neck has been broken. For some purposes where the contents of the bottle are not removed at a single operation it is desired to temporarily seal the bottle. It is for this reason that I provided the modified form shown. In this form of the invention I provide the neck 1 the same as in the preferred form of the invention which has the enlarged head 2. A cork is adapted to be received in the neck beneath the sealing disk as is shown in dotted lines in this figure and in order that the cork may be removed after the neck is broken the neck is weakened at the point 8. The neck is weakened by means of a scratch.

When the contents are placed in the bottle the cork disk 7 is placed on the end of the neck and the sealing disk 5 placed on the top thereof. By pressing upon the pointed top of the sealing disk the same will be expanded and engaged within the groove 3 formed in the enlarged head 2. After the sealing disk has been put in position it cannot be removed as no edges are exposed and the top thereof is smooth. When it is desired to remove the contents from the bottle it is only necessary to strike a light blow on the enlarged head 2 which will sever the head from the neck of the bottle at the point 4. In the modified form of the invention to remove the contents a light blow is made on the head 2 which will sever the neck at the point 8, thereby leaving the upper end of the cork exposed. The cork may then be removed and part of the contents removed and can then be replaced until it is again desired to remove the contents.

I have described the neck as being weakened by means of a scratch as distinguishing from an indentation molded in the neck as the surface of the glass must be fractured to cause the glass to split evenly and without splintering.

Having fully described my invention what I claim as new and desire to secure by Letters Patent is:—

1. In a non-refillable bottle comprising an enlarged annular head connected with the bottle at the open end thereof, said annular head provided with an annular groove on its interior, a retaining disk formed from a circular piece of material having a plurality of radially extending crimps for contracting the edge of said retaining disk, said retain-

5 ing disk also being convexed on its bottom face whereby the edge of said disk will extend into the annular groove in said head when a pressure is applied to the center of said disk, and a closure disk of impervious material interposed between said retaining disk and the top edge of the neck of the bottle.

10 2. In a non-refillable bottle comprising an enlarged annular head connected with the neck of the bottle at the open end thereof, said annular head provided with an annular groove on its interior, the inner wall of said groove being of semi-circular formation, a 15 retaining disk formed from a circular piece of material having a plurality of radially extending crimps for contracting the edges

of said retaining disk, said retaining disk also being convexed on its bottom face whereby the edge of said disk will extend 20 into the annular groove and be curved downwardly by the curved wall of said groove when a pressure is applied to the center of said disk, and a closure disk of impervious material interposed between said retaining 25 disk and the top edge of the neck of the bottle.

In testimony whereof I affix my signature in presence of two witnesses.

COLEMAN F. COOK.
